CONTAINER FOR OIL PRODUCTS OR THE LIKE

Earl L. Schaper and Bobbie G. Caldwell, Midland, Mich.,
and Carroll J. Macalusa, Baton Rouge, La., assignors to The Dow Chemical Company, Midland, Mich., a corporation of Delaware

Continuation of design applications Ser. No. 437 and Ser.
No. 437, Jan. 4, 1966. This application Dec. 19, 1966,
Ser. No. 5,116

Term of patent 14 years

(Cl. D58—17)

Fig. 1

This application is a continuation of applications Ser. Nos. D. 437 and D. 438, both filed Jan. 4, 1966 and now abandoned.

We claim:

The ornamental design for a container for oil products or the like, as shown and described.
